UNITED STATES PATENT OFFICE.

HALVER O. HALVERSON, OF HAWLEY, MINNESOTA.

BUNDLE-LOADER.

No. 839,288.

Specification of Letters Patent.

Patented Dec. 25, 1906.

Application filed November 10, 1905. Serial No. 286,767.

To all whom it may concern:

Be it known that I, HALVER O. HALVERSON, a citizen of the United States, residing at Hawley, in the county of Clay and State of Minnesota, have invented a new and useful Improvement in Bundle-Loaders, of which the following is a specification.

This invention relates to a device adapted to be used in loading bundles of grain, hay, 10 hemp, clover, and the like materials upon a wagon, the material to be loaded being picked up by the device from the ground and delivered to an endless carrier which in turn conveys it to the wagon, the loader and 15 wagon being driven side by side.

The special object of the device is to load grain in such a manner that the loose grain 20 will be delivered to the wagon as well as the bundles, thus avoiding the waste of all grain 25 which falls from the bundles or which has not been tied.

The invention consists of the novel features of construction hereinafter fully described, pointed out in the claims, and shown 25 in the accompanying drawings, in which—

Figure 1 is a plan view of the device complete. Fig. 2 is a side elevation of the frame and gathering mechanism, the elevator being shown in dotted lines. Fig. 3 is a plan view 30 of the device with the elevator removed. Fig. 4 is a side elevation of the elevator, the frame being shown in transverse section. Fig. 5 is a detail perspective view of a sliding block and a portion of a crank-shaft journal 35 naled therein.

In the drawings, 1 represents a rectangular frame provided with parallel cross-pieces 2, on which is journaled a shaft 3, which forms the drive-shaft of the device, and on this 40 shaft is the ground-wheel 4, which supports that portion of the frame, and upon the opposite end of the frame is journaled a shaft 5, upon which is a similar wheel 6, the entire frame 1 being supported by the wheels 4 and 6.

45 Sprocket-wheels 7 and 8 are fixed upon the shaft 3, and upon an end portion of this shaft is pivoted a forwardly-extending arm 9, and a similar arm 10 is pivoted upon the inner end of the shaft 5. In these arms 9 and 50 10 is rotatably journaled a compound cranked shaft 11, which at one end is provided with a sprocket-wheel 12, and a sprocket-chain 13 travels over the sprocket-wheels 7 and 12 and rotates the cranked shaft 11.

55 Downwardly and forwardly projecting fin-

gers 14 extend from the forward side of a rockable finger-head 14^a, pivoted in bearings 14^b, carried by the frame 1 and below and in advance of the cranked shaft 11, and these fingers collect the bundles and the loose grain 60 or other material to be loaded. Arms 15 are pivotally mounted intermediate their ends upon the cranked portions of the shaft 11 and at their outer free ends carry cross-heads 16, which cross-heads are provided 65 with a plurality of fingers 17, which deliver the material collected by the fingers 14 to an endless carrier to be described hereinafter.

To provide for the adjustment vertically of the shaft 11, the rear end of the frame 1 carries an upwardly and forwardly extending beam 18, and to the forward end of this beam is secured a curved sleeve 19, which is longitudinally slotted upon the sides, as shown at 20. In this sleeve slides a curved block 21, 70 through which the cranked shaft 11 freely passes. A standard 22 is mounted upon the beam 18 and at its upper end carries an idle pulley 23, and a similar pulley 24 is carried in a suitable bracket placed upon the beam 18 75 immediately to the rear of the standard 22. Upon the rear of the beam 18 is mounted a quadrant 25, upon which works a lever 26, arranged within easy reach of a seat 27. A cable 28 is connected at its rear end to the 80 lever 25 and passes forwardly under the pulley 24 and over the pulley 23 and at its forward end is connected to the sliding block 21.

Upon the beam 18 is pivoted a triangular-shaped frame 29, arranged transversely with 85 respect to the beam, and pivot-links 30 connect the ends of the frame 29 to the ends of the arms 15. From the fingers 14 and adjacent the side of the frame 1 extends a plurality of upwardly and rearwardly curved 90 short fingers 31, which serve to guide the bundles, hay, or the like in their passage from the fingers to the elevator or carrier.

In order to adjust the fingers 14 with respect to the ground, short arms 32 are fixed 100 at the opposite ends of the finger-head, and along the rear side of the frame extends a rotatable rod 33, adapted to be partially rotated by means of a lever 34, which works over a quadrant 35, also arranged adjacent 105 the seat 27. Upon each end of the rod is a short arm 36, and the arms 32 and 36 at each end of the frame are connected by a rod 37. Short shafts 38 and 39 are journaled on the cross-pieces 2 adjacent the rear side of the 110

frame, and the sprocket-wheel 40 is fixed on the shaft 39, and an idler 41 is mounted on the shaft 38. A sprocket-chain 42 runs over the sprocket-wheels 8 and 40, the under portion of the chain being guided by the idler 41. The short shaft 43 is journaled on the rear side of the frame and carries a beveled pinion 44, which meshes with a beveled pinion 45, carried by the shaft 39, and at its outer end the shaft 43 carries a drive-gear 46.

Mounted upon the frame 1 is a suitable platform having a level or horizontal portion 47, and an upwardly-inclined portion 49, which extends laterally above the wheel 4. For conveying the grain I provide a carrier comprising a plurality of spiked slats 48, the ends of which are connected to suitable endless chains 50, which are of the usual form of link sprocket-chains, and these chains travel over sprocket-wheels 51, mounted upon suitably-arranged shafts 52.

It will be obvious that by having the platform with the horizontal and inclined portions 47 and 49 arranged beneath and adjacent the carrier the loss of loose grains is prevented, as such grains are collected upon the level portion of the platform instead of being scattered upon the ground.

The carrier is driven by a sprocket-chain 53, which runs over the gear-wheel 46, and a suitable sprocket-wheel 54, carried by the uppermost shaft 52.

In operation the grain or material collected by the fingers 14 is thrown upon the carrier by the fingers 17, carried by the rotating arms 15, and by the carrier is conveyed to the wagon or other place into which the material is to be placed. It will be noted that the carrier is arranged transversely between the front and rear sides of the frame 1, and the upwardly-inclined portion of the carrier, which is supported by a suitable brace-bar 55, projects above and beyond one end of the frame. A suitable tongue 56 is also connected to this end of the frame.

Having thus fully described my invention,

what I claim as new, and desire to secure by Letters Patent, is—

1. The combination with a frame, of an endless carrier thereon, of a cranked shaft 50 rotatably mounted above the front of the frame, means for rotating the said shaft, arms pivoted intermediate their ends upon the cranked portion of the shaft, fingers carried by an end of each of said arms, and pivotally-mounted means for connecting together the opposite ends of the arms.

2. In a bundle-loader, the combination with a suitable wheeled frame, arms pivotally mounted upon said frame, a cranked shaft loosely journaled in the free end portions of said arms, finger-carrying arms journaled upon the cranked portions of the said shaft, a curved and slotted sleeve supported above the frame, a sliding curved block in 65 the sleeve, the said shaft passing through the slots of the sleeve and loosely through the said block, and means for sliding the block in the sleeve.

3. A device of the kind described comprising a frame, an endless, belt-like carrier, carried by the frame, means for driving the carrier, pivot-arms carried by the frame, a cranked shaft journaled in said arms adjacent their free ends, arms mounted intermediate their ends upon the cranked portions of said shaft, fingers carried by said arms; an upwardly and forwardly extending beam carried by the frame, a sleeve longitudinally curved and having slotted sides carried by 80 the said beam, a slidable block in the sleeve, the cranked shaft passing through said block and the slots of the sleeve, a second frame mounted on an upwardly-extending beam, links pivotally connected to the ends of said 85 frame and to the arms carrying the fingers, means for rotating the cranked shaft, and means for sliding the block in the sleeve.

HALVER O. HALVERSON.
